[57] CLAIM

The ornamental design for a truck bed liner, as shown and described.

DESCRIPTION

FIG. 1 is a top plan view of the truck bed liner showing my new design;

FIG. 2 is a side elevational view thereof;

FIG. 3 is a rear end elevational view thereof;

FIG. 4 is an enlarged fragmentary transverse vertical sectional view thereof through one-half of the liner taken along the line 4—4 of FIG. 1;

FIG. 5 is an enlarged fragmentary transverse vertical sectional view thereof through one-half of the liner taken along the line 5—5 of FIG. 1;

FIG. 6 is an enlarged fragmentary longitudinal sectional view thereof taken along the line 6—6 of FIG. 1; and

FIG. 7 is an enlarged fragmentary longitudinal sectional view thereof taken along the line 7—7 of FIG. 1.
